UNITED STATES PATENT OFFICE.

CLARENCE FREDERIC DAVY AND THOMAS RICHARDSON, OF FITZROY, NEW ZEALAND.

NON-REFILLABLE BOTTLE.

1,081,491.

Specification of Letters Patent. Patented Dec. 16, 1913.

Application filed June 20, 1912. Serial No. 704,760.

To all whom it may concern:

Be it known that we, CLARENCE FREDERIC DAVY and THOMAS RICHARDSON, both citizens of the Dominion of New Zealand, and 5 residing at Fitzroy, in the Provincial District of Taranaki, in the Dominion of New Zealand, have invented certain new and useful Improvements in Non-Refillable Bottles, of which the following is a specification.

10 This invention relates to that class of bottles which are constructed to prevent fraudulent refilling.

According to our invention, a cylinder having a closed top is adapted to fit the 15 neck of a bottle, the said neck having an internal circumferential recess into which project a washer of cork, rubber or similar resilient material held in a groove upon the exterior of the cylinder, and crescent shaped 20 members having a pad of cork or the like midway between their extremities, the said members being held in another groove also upon the exterior of the cylinder. Instead of crescent shaped members a gapped ring 25 or a second ring of cork, may be employed, or an extra ring of cork. At the top of the cylinder is a flange having mutilations, which are out of register with corresponding mutilations in another flange lower 30 down upon the cylinder. Below these flanges the cylinder is provided with lateral ports. The interior of the top of the cylinder is recessed upwardly. A sleeve having a groove fitted with a washer of cork, 35 rubber or similar resilient material to fit the interior of the cylinder has a flange which fits against the bottom of the cylinder. The sleeve has lateral ports which do not register with the lateral ports of the cylinder. A 40 hollow piston or plug, slideable in the sleeve, and adapted to seat upon a seating formed at the bottom of the sleeve, closes the ports of the sleeve during the movement of the bottle from an inverted to an upright position. A ball, heavier than water, is located 45 within the cylinder, and is adapted to push the piston into the sleeve by gravity. A second ball, located within the piston and lighter than water has a seating formed 50 upon the aforementioned internal flange of the sleeve.

In a modification the invention is adapted for use upon bottles for containing sauces, patent medicines and the like.

55 The drawing herewith illustrates the invention.

Figure 1, is a sectional elevation of a bottle embodying our invention. Fig. 2, is a plan of the cylinder. Fig. 3, is a sectional plan on line A—A Fig. 1, and Fig. 4, a 60 sectional plan on line B—B Fig. 1. Fig. 5, is a perspective view of a gapped ring. Fig. 6, is a sectional elevation showing a modified form of our invention.

Referring to the drawing, the cylinder 1 65 has a closed top 2 and is adapted to fit the neck 3 of the bottle 4 by means of a cork, rubber or the like washer 5, which is held in a groove 6 formed upon the exterior of the cylinder, and is adapted to swell into 70 a recess 7 after being squeezed into the recess 6 during the operation of inserting the cylinder into the neck of the bottle. If the washer 5 should deteriorate or be destroyed, it might be possible to extract the 75 cylinder, refill the bottle and replace the cylinder. To prevent such fraudulent action crescent shaped members 8 and 9 (see Fig. 4) are fitted into a groove 10 also formed upon the exterior of the cylinder. 80

Cork pads 11 and 12 are fixed to the members 8 and 9 midway between their extremities. The cork allows the members 8 and 9 to pass into the groove 10 while the cylinder is being inserted into the neck of the bottle 85 and forces the said members partially into the recess 7. These members thus render it impossible to withdraw the cylinder as they extend into the recess 7. At the top of the cylinder is a flange 13 mutilated by gaps 14 90 (see Fig. 2) which gaps are out of register with the gaps 15 of a correspondingly mutilated flange 16 located lower down upon the cylinder. The gaps in the flanges 13 and 16 allow liquid to pass out of the bottle but prevent the introduction of a wire 95 for the fraudulent purpose of tampering with the parts contained in the interior of the cylinder. Below the flange 16 the cylinder 1 is provided with lateral ports 17, and the 100 top of the cylinder has an internal spherical recess 18.

A sleeve 20, having a groove 21, filled with a cork, rubber or the like washer 22 to fit the interior of the cylinder 1, has a 105 flange 23 which fits against the bottom of the cylinder 1. The sleeve has lateral ports 24 which do not register with the ports 17. A hollow piston or plug 25 slideable in the sleeve 20 closes the ports 24 when the said piston or plug is at rest upon the internal flange 29, as shown in Fig. 1. A ball 26

heavier than water is located within the cylinder 1, and is adapted to push the piston 25 into the sleeve 20 by gravity. The radius of the ball 26 is less than the radius 5 of the recess 18, so that the ball is not held by suction, but will readily run down upon the piston, when the bottle is partially inverted. A second ball 27 lighter than water and located within the piston, has a seating 10 28 formed upon the beforementioned flange 29. If the pressure is applied to the mouth of the bottle, the sleeve 20, balls 26 and 27 the piston 25 and the washer 22 would be forced into the bottle, which might then be 15 refilled. But the fact that the above parts were present in the liquid contained by the bottle would be ample evidence that the contents has been tampered with, and would prevent a purchaser from buying a bottle 20 so tampered with.

The members 8 and 9 may be made of glass, or other suitable material. If the members are made of resilient material the cork pads 11 and 12 are not necessary, and the 25 members may then be made in one piece in the shape of a ring 30 with a gap 31, see Fig. 5.

When the bottle is inverted for the purpose of pouring out liquids, the ball 26 falls 30 away and the piston descends beyond the ports in the sleeve, thus allowing the liquid to flow through the said ports, through the ports in the cylinder, and through the gaps in the flanges 13 and 16. An air hole 13^a 35 in the cylinder 1 allows the piston to descend quickly and consequently the liquid flows at once. Upon returning the bottle to its vertical position the ball 26 falls upon or rolls against the piston, which thereby 40 closes the ports in the sleeve. If an attempt is made to fill the bottle while inverted, the ball 27, being floatable in water, will close upon its seat and prevent such fraudulent action.

Fig. 6 shows a modified form of the invention suitable for bottles used for containing sauces, patent medicines and the like. The internal sleeve 20 is shortened and the hollow piston 25 is dispensed with.

The balls 33 and 34 are located within the 50 cylinder 35, which corresponds to the cylinder 1 previously described. The ball 33 is heavier than water and the ball 34 floats in water. The cylinder 35 has ports 36 and 37, and the ball 34 has a seating 38 at the 55 bottom of the sleeve 20. The ball 33 falls into the recess 39 formed in the top of the cylinder and the ball 34 falls back to allow liquid to pass when the bottle is inverted, and the ball 33 closes the ball 34 upon its 60 seat during the movement of restoring the bottle to its upright position. If an attempt is made to fill the bottle with liquid while inverted, the ball 34 floats upon the liquid and stops its entrance into the bottle. 65

What we do claim and desire to secure by Letters Patent of the United States is:—

A non-refillable bottle, including a cylinder having circumferential ports intermediate of its length, said cylinder being 70 provided around its upper edge with a flange having a plurality of mutilations therein and a short interval below said flange with a second flange also having a plurality of mutilations therein, alternating with the 75 mutilations of the aforesaid flange, said cylinder also having arranged in its lower end a sleeve provided with ports out of register with the aforesaid ports of said cylinder, said sleeve having arranged within 80 itself a closed upper end hollow piston and provided with a port in the bottom, a buoyant valve seated in said port and arranged within said piston, said piston itself controlling the ports in said sleeve, and a non- 85 buoyant valve arranged within the upper end of said sleeve and adapted to engage the closed upper end of said piston and limited in its upward movement by the upper end of said cylinder. 90

In testimony whereof we have signed our names to this specification in the presence of two witnesses.

CLARENCE FREDERIC DAVY.
THOMAS RICHARDSON.
